Inventor
Herman Kistner
By his Attorney Fred C. Fischer

UNITED STATES PATENT OFFICE.

HERMAN KISTNER, OF ELIZABETH, NEW JERSEY, ASSIGNOR, BY MESNE ASSIGNMENTS, TO VICTORY HAMMERED PISTON RING COMPANY, OF NEWARK, NEW JERSEY, A CORPORATION OF NEW JERSEY.

PACKING-RING.

1,393,542.

Specification of Letters Patent.

Patented Oct. 11, 1921.

Application filed May 12, 1919. Serial No. 296,324.

To all whom it may concern:

Be it known that I, HERMAN KISTNER, a citizen of the United States, residing in the city of Elizabeth, in the county of Union 5 and State of New Jersey, have invented certain new and useful Improvements in Packing-Rings, of which the following is a full, clear, and exact description, such as will enable others skilled in the art to which it 10 pertains to make and use the same, reference being had to the accompanying drawings, and to the numerals of reference marked thereon, forming a part of this specification.

My invention relates to packing rings and 15 more especially to metallic spring packing rings for pistons of steam or internal combustion engines, pumps and the like.

One of the objects of my invention is to provide a packing ring for this purpose, the 20 structure of which is so simplified as to render the same positive and effective in operation, durable in use, simple and inexpensive in construction, thereby reducing the cost of manufacture to a minimum.

25 A further object of my invention is to provide a packing ring, which will maintain at all times, a tight but resilient fit between the piston and the wall of the cylinder without giving undue or frictional resistance 30 against the walls, and one which owing to its construction and manufacture is adapted to more readily and automatically adjust itself as the contact surfaces become worn.

This I accomplish by giving the ring on 35 its peripheral edges, a hammer or a series of hammer blows, which compress the metal toward the center of the ring, thereby producing an angular effect. This angular effect, to the ordinary eye, would appear to have 40 been the result of a machine operation such as, for instance, eccentrically turning the inner peripheral edges of the ring on a lathe, but the angular effect instead, is produced by delivering the blows preferably, simultaneously, on both edges, thereby crowding the metal toward the center of the ring which produces the maximum degree of tension desired.

By delivering the blows on the inside edges 50 of the ring the uniformity of the ring is largely maintained, thereby avoiding subsequent operation and reducing the amount of metal to be removed to a minimum, thereby maintaining the maximum degree of tension

originally imparted to the ring by the angular blow, which has the effect of homogeneously crowding or uniting the particles of metal together. 55

With these ends in view, my invention consists of certain novelties of construction and arrangements of parts as hereinafter set forth and pointed out in the claim. While the preferred form of my invention is illustrated in the accompanying drawings, yet it is to be understood that minor changes may 60 be made without departing from the scope thereof.

In the drawings,

Figure 1 represents a plan view of my improved hammered piston ring; and 70

Fig. 2 represents a sectional view taken along the line $x-x$ of Fig. 1, looking in the direction indicated by the arrow.

Similar numerals of reference refer to like parts throughout the specification and drawings. 75

In the drawings, 1 represents a packing ring, preferably composed of comparatively soft, smooth wearing metal, such as cast iron of proper quality, although any other suitable material may be employed, if desired. 80

The ends of the ring, preferably, overlap, being cut longitudinally and transversely of the packing ring 1, so as to form a scarfed joint, although a square, tapered or other form of juncture may be used. The ring is further provided with beveled surfaces 2—2 eccentrically formed, preferably on the inner peripheral edges of the ring, and where the ring is to be secured in the retaining groove of an engine cylinder, these beveled surfaces would be provided on the outer peripheral edges of the ring, in order to impart to the ring the desired tension required. 85

The beveled faces or surfaces, are the results of delivering the blow or blows upon the peripheral edges of the ring, in order to crowd the metal in the direction indicated by the arrows, namely, toward the center of the ring, thereby homogeneously crowding or uniting the particles of metal together, and imparting thereto the maximum degree of tension, as distinguished from delivering the blows upon the inner curved surfaces of the ring, which experience has demonstrated, spreads and in many cases, fractures the metal, which results in a large percentage of breakage during the manufacture. Before 90

100

105

the hammering operation takes place, the ring is of a uniform cross-section through out, and by placing the said ring in a suitable device, a blow from a suitable punch or hammer is preferably, simultaneously delivered upon the inner or outer peripheral edges of the ring, to produce eccentrically arranged hammered surfaces by homogeneously uniting or crowding the particles of metal together, and imparting thereto the maximum degree of tension. It is immaterial how the blows of the punch or hammer are distributed, whether the operation is done simultaneously by one blow delivered upon each of the peripheral edges, or by a series of blows delivered, so long as a continuous compacting along the peripheral edges of the ring is produced.

Experience has demonstrated that the organization above described is a highly efficient one, and while I have shown the preferred embodiment of my present invention,

I do not wish to be limited to the exact details of construction shown and described, as obvious modifications thereof, not involving the exercise of my invention, may be made by any skilled mechanic, and such departure from what is herein set forth, I consider within the scope and terms of my claim.

Having thus described my invention, what I claim as new and desire to secure by Letters Patent is:—

A metal packing ring consisting of a split ring having the metal at its edges compacted to form an eccentrically arranged inner beveled edge, the bevel of which is greatest at the region opposite the split and decreases in both directions.

This specification signed and witnessed this 10th day of January, 1919.

HERMAN KISTNER.
